ABSTRACT: This application discloses inhibiting of explosions in coal mines and the like by broadcasting an inert material in the mine in the form of finely divided shells of bivalves.

INHIBITING EXPLOSIONS IN COAL MINES AND THE LIKE

This invention relates to inhibition of explosions in coal mines and the like by introduction of inert material into the mines. More particularly it relates to use of finely divided bivalve shell material as an inert material, which will inhibit explosions and also improve health and working conditions in mines.

Removal of carboniferous deposits from the earth in the form of coal or lignite is widespread and occurs in many different parts of the world. Removal may be by strip mining or by underground, or deep, mining. Underground mining normally employs a series of parallel entries or haulageways extending from a shaft or portal to the working face and having transversely extending crosscuts at intervals.

The steps of blasting, drilling, and cutting, and also operation of continuous mining machines produce substantial quantities of coal dust, rock dust, and fumes. The terms "coal" and "coal dust" here are intended to be comprehensive of carboniferous materials including bituminous coal and lignite, and dusts thereof. Also, the freshly exposed coal face evolves substantial quantities of methane. If no provision is made for adequate ventilation the buildup of fumes and dust would make conditions intolerable for the miners. Also the concentration of methane in the atmosphere would increase to form an explosive mixture with the air. Accordingly, a moving airstream is customarily induced or directed through the workings so that there is a continuous supply of fresh air to the working face and an exhaust from the working face to the atmosphere.

As has been noted above, the various mining operations produce fine coal dust in varying amounts. The moving airstream employed for ventilation tends to carry the dust throughout the mine, and hat dust is sometimes known as "float coal". Finely divided coal dust tends to be unstable because of the high ratio of surface area to volume, and may lead to dust explosions in the confined places. Also, a relatively minor explosion in one part of the mine may be propagated throughout the mine by the presence of fine coal dust.

It has long been customary, both as a matter of good mining practice and because of legal requirements, to inhibit and suppress mine explosions by providing an adequate quantity of fresh air to remove combustible gases. Additionally the coal dust has been diluted and intermingled with an inert rock dust material to prevent propagation of an explosion in the coal dust. While various rock dusts are acceptable, the most commonly used appears to be finely divided limestone which is distributed throughout the mine including the airways carrying methane to the atmosphere. Common rock dusts are generally denser than coal dust, and when rock dust and coal dust are carried in a common airstream, the rock dust tends to fall out of the airstream more quickly than the coal dust.

It has been observed that many limestones are relatively high in silica content, that is they contain 5 percent or more silica. When the finely divided rock dust, including silica, is entrained in the airstream in a mine it is likely to be inhaled by miners. Recent studies increasingly evidence that the silica is injurious to the health of the miners. As a result mining operations are now rock dusted with limestone having a maximum silica content of 5 percent, and preferably lower. Obtaining such material, particularly of lower silica content, is often inconvenient and/or expensive, however.

I have invented new methods for inhibiting explosions in coal mines and the like. I employ a common and readily obtainable material and by appropriate treatment of it attain a far superior result than any previously attainable while maintaining a price which is comparable with prior materials.

Moreover, the danger to miners by reason of silica inhalation resulting from rock dusting is virtually eliminated. I employ as a starting material, the discarded shells of bivalves which are found in profuse deposits in ocean areas and are in

abundant supply. Old shells, in the order of 5,000 years old, have proven to be highly satisfactory. I wash the shells to remove loose silica, such as sand, from them. Thereafter the shells are ground to finely divided form, introduced into the mine and broadcast in the mine including onto the walls of the mine and into the airstream. As used here, the term "walls" includes the horizontal walls (floor and ceiling) as well as the vertical walls. The shell material may be broadcast by shovel, by conventional machinery, or by injection into a moving airstream at appropriate location.

Preferably the bivalve shell material is reduced to a form in which a major fraction, preferably 80 percent or more, will pass a standard 200 mesh screen. By reason of the manner in which bivalve shells are formed, they appear to have laminar layers and be readily reduced to finely divided form. The density of the shell material more nearly approaches the density of coal than does rock dust. It is thought that the laminar form causes the finely divided shell material to be in the form of platelets and that the relatively large surface area relative to the volume helps to carry the material in a moving airstream with float coal. In a preferred form the bivalve shells are those of oysters taken from the Gulf of Mexico. An analysis of the shell material (when properly washed) shows that it is substantially all calcium carbonate and contains only small amounts of silica, less than 1 percent. Reduction by air impact milling followed by air classification has been particularly useful in obtaining a suitable shell material without substantial amounts of an excessively fine fraction. Explosion tests indicate that the quantity of shell material required to inhibit explosions is less than the amount of rock dust required.

While I have described a present preferred embodiment of my invention, it is to be understood that the invention may be otherwise variously practiced within the scope of the following claims.

- 35 1. I claim:
1. The method of treating coal mines and the like to inhibit explosions therein which comprises introducing finely divided bivalve shell material into a mine and broadcasting said shell material within the mine.
  2. The method of claim 1 in which broadcasting of the finely divided shell material intermixes the shell material with finely divided carboniferous material in sufficient amount to prevent propagation of an explosion in the finely divided carboniferous material.
  3. The method of claim 2 in which a major fraction of the finely divided shell material is minus 200 mesh in size.
  4. The method of treating coal mines and the like to inhibit explosions therein which comprises the steps of:
    - collecting the shells of bivalves;
    - washing the shells to remove foreign material from the shells;
    - reducing the bivalve shells to finely divided form;
    - broadcasting the finely divided bivalve shell material within the mine.
  5. The method of claim 4 in which broadcasting of the finely divided shell material intermixes the shell material with finely divided carboniferous material in sufficient amount to prevent propagation of an explosion in the finely divided carboniferous material.
  6. The method of claim 4 in which a major fraction of the finely divided shell material is minus 200 mesh in size.
  7. The method of treating coal mines and the like to inhibit explosions therein which comprises the steps of:
    - collecting the shells of bivalves;
    - washing the shells to remove foreign material from the shells;
    - reducing the shells to a finely divided form in an air impact pulverizer;
    - classifying the size of the finely divided particles in an air classifier;
    - broadcasting the finely divided bivalve shell material in the mine into a moving airstream and onto the walls.
